WIRING SYSTEM FOR METAL WALLS

Earl F. Hauserman and John A. Bohnsack, Cleveland Heights, Ohio, assignors to The E. F. Hauserman Company, Cleveland, Ohio, a corporation of Ohio

Application February 18, 1932, Serial No. 593,800

7 Claims. (Cl. 189—34)

This invention relates to sectional partitions, and particularly the class of sectional metal partitions constructed of hollow metal. It has been customary to provide race-ways in the hollow members of such partitions for the purpose of concealing electric wiring, but such electric wiring must be fished or pulled through the various members and holes. It is frequently desirable to make changes in the arrangement of such partitions, such as for instance interchanging a door section with a panel section, in which event it is necessary to disconnect and remove the electric wiring. If the wiring system is such that the wires must be pulled, or fished, heavy and comparatively inflexible cables, such as for instance lead covered telephone cables, are comparatively difficult to install by pulling through longitudinally. Present building practice frequently provides ducts in the floors, with various outlets giving access to the partitions at the floor line and where such is the case, the wiring is usually carried through the base member of the partition. Where wires run through the base it is desirable to provide means for extending such wires past door openings without necessarily bringing them over and around the opening. It is among the objects of this invention to provide a wiring system for sectional partitions which will permit of interchanging panel and door sections without disconnecting the wires and which will permit of extending the wires continuously along the base member and past door openings, and which will permit of the transverse insertion of conduits.

To the accomplishment of the foregoing and related ends, the invention then consists of the features hereinafter fully described and particularly pointed out in the claims, the following description, and the annexed drawing, setting forth in detail but one of the various ways in which the principles of the invention may be applied.

In said annexed drawing:

Fig. I is a front elevational view of a portion of a sectional partition constructed in accordance with this invention; Fig. II is a transverse vertical section on larger scale taken on a plane indicated by the line II—II of Fig. I; Fig. III is a front elevational view of a portion of Fig. I on a larger scale, with the cover plates and cover members removed; Fig. IV is a partial elevational view of the inside of a door opening with the door leaf removed; Fig. V is a longitudinal horizontal section taken on a plane indicated by the line V—V of Fig. III, the threshold being indicated by dotted lines; Fig. VI is a perspective view of a

floor positioning member; and Fig. VII is a perspective view of a shim.

Partition walls are customarily made up of a series of panel sections and door sections assembled in alignment. Support members are used between adjacent sections and these may take the form of separately erectable members or may constitute a part of the partition section. In the construction disclosed, panel members 20 are carried by support members 21. The support members of adjacent partition sections are assembled in alignment and a facing member 41 provided to cover the juncture, using any of the various well known securing devices. A positioning horizontal 22 extends between the support members at either side of the panel member and is preferably spaced away from and below the lower edge of the panel member. The positioning horizontal is secured to the support members by welding, bolting, riveting, or the like and may conveniently take the form of a channel with upstanding flanges 23 forming a trough adaptable, as seen for instance with reference to Figs. II and III, to carry wires of a given potential and separate them from wires of a different potential beneath. The central portion of this positioning horizontal is provided with a series of holes 52. Clips 24 are provided in pairs and extend through and are located by the holes in the positioning horizontal and engaged against the panel member. These clips are provided with rounded end portions 26 and 27 and with slotted holes 31. A bolt 53 clamps a pair of clips against opposite sides of the panel members and serves to hold them in independently vertically adjustable position. Re-inforcing blisters 54 are embossed on the clips to prevent bending. Cover members 28 extend between the support members at either side of the panel members and may take the form of a channel with indent flanges and suitable moldings to constitute a finished base and resiliently engage over the clips 24. The cover members are thus readily removable by springing out of engagement with the clips. The support members are provided with notches 29 which permit passage of conduits 32 through the support members and into the space between the cover members. Cover plates 51 cover the notched out portions of the support members and overlap the ends of the cover members. Such cover plates have the appearance of plinths and may be resiliently secured to the facing members 41, or otherwise held to permit of ready disengagement.

Where doors are desired to strike frame 33 is carried by the support members by suitable

means, preferably providing vertical adjustment between the strike frame and the supports. A threshold 42 preferably of non-corrosive metal in channel form extends between the support members on either side of the strike frame and is suitably fastened to the floor. The ends of the threshold are coped, or notched, to the contour of the strike frame, thus making it possible to lift the threshold without disturbing the strike frame, at the same time preventing lateral displacement of the threshold.

Since the floors encountered in building construction vary considerably in level, it is necessary to provide means of installing partitions at a common level and for this purpose we provide shims 70 which are provided with semi-punchings 71 so that a plurality of such shims will engage one another when stacked. A floor positioning member 60 is provided and is so contoured as to engage the semi-punchings on the shims and be positioned thereby. This floor positioning member engages and positions the support members against lateral displacement. The shims and floor positioning member are so contoured as to permit conduits to be laid from the threshold past and over the shims and into the space between adjacent support members.

It will thus be seen that removal of the cover plates and cover members permits conduits to be inserted transversely continuously along the partition under the panel members and through the notches in the support members, and elevating the threshold permits such conduits to be transversely inserted under the door sections. It will further be seen that since no severe bends need be made, a comparatively rigid conduit is readily insertable. It will further be seen that it is possible to remove and replace a partition section without severing or disconnecting the conduit which runs therethrough and it is thus possible to interchange panel and door sections without disturbing the electrical system.

Other modes of applying the principle of the invention may be employed, change being made as regards details disclosed, provided the means stated by any of the following claims or the equivalent of such be employed.

We therefore particularly point out and distinctly claim as our invention:

1. In partition construction, a series of aligned panel units; cover plates removably mounted thereon; support members between adjacent panel units having notches opposite such cover plates and cover members over such support members and such notches, the assemblage presenting a continuous conduit compartment accessible for transverse insertion of a conduit through said notches and behind said cover plates and cover members.

2. In partition construction, a series of panel units and door units, support members between adjacent units and having notches and shims supporting such support members and so contoured as to permit transverse insertion of a conduit partially beneath such support members.

3. In partition construction, a door unit having a strike frame and support members for such strike frame at each side thereof and a hollow threshold extending across the bottom of such strike frame; and a continuous conduit transversely insertable through notches in said supports and beneath such strike frame through said threshold.

4. In partition construction, a panel unit comprising a panel member; support members extending below such panel member; a positioning horizontal below such panel member and spaced away therefrom; vertically adjustable clip members frictionally engaging such panel member and positioning horizontal; notches in such support members and cover plates extending between said supports and removably secured to said clips.

5. In partition construction, a series of support members spaced along at intervals; notches in such supports; removable cover plates extending between pairs of supports; and removable cover members overlapping the notches in each support and the cover plates on each side thereof, the assemblage presenting a continuous compartment accessible for transverse insertion of a conduit by removal of such cover plates and cover members.

6. In partition construction, a series of aligned panel and door units and continuous passageway means therein along the floor portion exposable without any interrupting obstruction for receiving electric conductors by bodily lateral movement, including a positioning member at the lower part of each panel, rounded projections carried by said positioning member, a hollow sheet metal cover resiliently engageable over said rounded projections, and a movable hollow sheet metal door-threshold.

7. In partition construction, a series of aligned panel and door units and continuous passageway means therein along the floor portion exposable without any interrupting obstruction for receiving electric conductors by bodily lateral movement, including a positioning member at the lower part of each panel, rounded projections carried by said positioning member, a hollow sheet metal cover resiliently engageable over said rounded projections, a movable hollow sheet metal door-threshold, and means for spacing the conductors into two groups in such passageway.

EARL F. HAUSERMAN.
JOHN A. BOHNSACK.
